UNITED STATES PATENT OFFICE.

WILLIAM G. ALLEN, OF HARTFORD, CONNECTICUT.

PUNCH PRESS.

Application filed May 19, 1921. Serial No. 470,799.

To all whom it may concern:

Be it known that I, WILLIAM G. ALLEN, a citizen of the United States, residing at Hartford, in the county of Hartford and 5 State of Connecticut, have invented a new and useful Improvement in Punch Presses, of which the following is a specification.

This invention relates to those presses which are designed for punching and drawing or otherwise blanking and dieing sheet metal and other sheet material, of the class in which the driving mechanism is arranged on the frame below the punch and die or other tools. Machines of this class are 10 illustrated in U. S. Patents to Wright No. 1,270,913, July 2, 1918, and Smith No. 1,338,335, April 7, 1920. In the old types of these machines the power of the driving 15 crank that has its side thrusts as well as its vertical pull and push, is applied to a lower gate which slides up and down the frame near the base and which is connected by rods with an upper crosshead that carries the punch or movable die. The punch heads 20 of these machines are subjected to vertical strains only but are not supported with sufficient rigidity to perform delicate work accurately, particularly after some use and the guiding parts become worn by the 25 heavy work to which they are subjected.

The object of this invention is to construct a machine of this class which is cheap to build, rugged and powerful in use yet relatively light in weight and which will 30 perform accurate work for a long period, and such wear as results can be readily taken up when necessary.

Machines which embody the present invention are constructed with driving mechanisms located in the frame below the tools 40 and connected with gates that reciprocate in adjustable ways near the base of the frame, and the lower gates are connected by rods with upper tool carrying gates that 45 reciprocate in adjustable ways near the top of the frame, whereby the tool gates are firmly supported and rigidly guided in their reciprocation, without any possibility of spring or undue strains on the connections 50 between the upper and lower gates which will cause wear on or add load to the moving parts.

The invention is primarily illustrated as applied to a double acting punching and 55 drawing press and Fig. 1 shows a front elevation of such a press. Fig. 2 shows a side

elevation of the same press with a portion of the frame broken away. Fig. 3 is a view looking at the top of the press with the driving pulley omitted. Fig. 4 is a horizontal section looking down on the plane indicated by the dotted line 4—4 on Fig. 1. Fig. 5 illustrates a modified manner of forming the supporting frame so that the action will be inclined rather than strictly 60 vertical. Fig. 6 is a detail of the means employed for fastening the frame sections of the modified construction. Fig. 7 shows a front elevation of a single acting press which embodies the invention. Fig. 8 70 shows a side elevation of the single acting press. Fig. 9 is a plan of the single acting press. Fig. 10 is a section on the plane 10—10 on Fig. 7.

The frame of the press illustrated is a 75 casting having two side members 1 that are connected at the back by a web 2, at the bottom by a base 3, and a little above the middle by a cross bracket 4 which forms the bed upon which the die 5 is placed. The frame however 80 may be made in parts if desired. The driving shaft 6 which is supported by suitable bearings near the middle of the frame has a pulley 7 and a clutch 8 of common form that is arranged to connect and disconnect 85 the pulley with the shaft by the movement of the treadle 9. At the center the shaft has a crank 10 and on each side of the crank is a cam 11. Embracing each cam is a yoke 12 that has a roller 13 above and a roller 90 14 below resting against the cam. These yokes are adjustably connected by threaded links 15 with a vertically movable gate 16. The edges of this gate have V-shaped 95 grooves which are fitted to slide up and down upon V-shaped guiding tongues 17 and 18 which are secured to the inside of the walls of the frame. The guide 18 on one side is permanently secured in place while the guide 17 on the other side is 100 adapted to be adjusted toward the gate by screws 19.

At the top of the frame is a vertically movable gate 20 which has V-shaped grooves in its edges that fit V-shaped guiding 105 tongues 21 and 22 fastened to the inside of the frame, the guide 22 being permanently secured and the guide 21 being adjustably secured by screws 23. The upper gate 20 and the lower gate 16 are joined by rods 24 110 and 25, one being in front on one side, and the other being in back on the other side.

- These rods pass freely through holes in flanges 41 shaped to fit on the base flanges 39. These parts may be secured together with the upper section tipped to the desired angle by bolts 42 with their heads lying in slots in the upper section and their shanks 70 extending through holes in the lower section, as illustrated in Figs. 5 and 6.
- If it is desired to provide a knock out for removing a piece from the die, a cam 43 may be secured to the end of the crank shaft 75 6 which cam may engage a lever 44 on the shaft 45 provided with a rocker arm 46. The rocker arm is designed to push up against the end of a spring retracted plunger 47 that extends up through an opening in 80 the bed and die, as shown in Fig. 5.
- If it is desired to embody the invention in a single acting machine, that is, a press designed to merely punch or blank sheet metal or other material, the drawing punch 85 or ram, its gate, and the connections with the driving shaft, may be omitted. Such a single acting press is illustrated in Figs. 7 to 10 inclusive. With this arrangement the crank 48 on the driving shaft 49, that 90 is provided with pulley 50 and clutch 51, is connected by an adjustable pitman 52 with the lower gate 53. The lower gate is movable up and down on ways 54 and 55 on the sides of the frame below the crank shaft. 95 In this case the lower gate is connected with the upper gate 56, by all four rods 57, the upper gate being movable up and down on guide ways 58 and 59 on the sides of the frame over the die bed 60 which is located 100 above the crank shaft. These rods pass freely through holes in the die bed and holes in the gates which are larger in diameter than the diameters of the rods so that the gates may be accurately adjusted and then 105 the rods secured by the nuts 61 without putting any side strains on the gates or adding to the load.
- In machines constructed as herein described the upper tool carrying gate and the crosshead are entirely relieved of all strains except the direct line pull of the rods which are so mounted that they are not subjected to any frictional resistance. With the 110 driving mechanism set below the tools and the upper gates held in this manner great accuracy can be attained with powerful machines for the tool carrying parts are supported in such manner that they are not subjected to distortion or vibration. In the 115 double acting machine the crosshead is guided solely by the fit of the punch carrying ram in the upper gate, and it is subjected to no distortional strains by the connecting rods.
- The invention claimed is:
1. A press comprising a frame, a die bed on the frame, a driving shaft supported by the frame below the die bed, a reciprocating gate movable on guide-ways on the frame 120
  2. A press comprising a frame, a die bed on the frame, a driving shaft supported by the frame below the die bed, a reciprocating gate movable on guide-ways on the frame 125
  3. A press comprising a frame, a die bed on the frame, a driving shaft supported by the frame below the die bed, a reciprocating gate movable on guide-ways on the frame 130

below the driving shaft, an actuating connection between said gate and the driving shaft, a reciprocatory gate movable on guideways on the frame above the die bed, 5 a punch carried by said upper gate, rods connecting the lower gate and the upper gate, said rods passing freely through openings in the frame and in the gates, and means for securing the rods to the gates 10 after the gates have been located whereby there will be no frictional resistance to the movement of the rods and the rods will not transmit any transverse strains on the gates.

2. A press comprising a frame and die bed fixed on the frame below the top thereof, a driving shaft supported by the frame below the die bed, a reciprocatory gate movable on guide-ways on the frame below the driving shaft, an actuating connection between 15 said gate and the driving shaft, a reciprocatory gate mounted on guide-ways on the frame above the die bed, a punch carried by said upper gate, rods connecting the lower gate and the upper gate, said rods 20 passing through openings in the frame adjacent to the fixed die bed but unsupported by the frame, and means securing the rods to the gates.

3. A press comprising a frame, a die bed 30 fixed on the frame below the top thereof, a die on the die bed, a knock out movable through said die, a driving shaft supported by the frame below the die bed, means on the driving shaft for actuating said knock out, 35 a reciprocatory gate movable on guideways on the frame below the driving shaft, an actuating connection between said gate and the driving shaft, a reciprocatory gate movable on guide-ways on the frame above the 40 fixed die bed, a punch carried by said upper gate, rods connecting the lower gate and the upper gate, said rods passing through openings in the frame adjacent to the fixed die bed but unsupported by the 45 frame, and means securing the rods to the gates.

4. A press comprising a frame formed in sections, the upper section being supported on the lower section in such manner that it 50 may be inclined with relation thereto, means for securing the upper section of the frame to the lower section with the upper section tilted at an angle therewith, a die bed on the upper section of the frame, a driving 55 shaft supported by the upper section of the frame below the die bed, the axis of the shaft and center of oscillation of the upper section of the frame being coincident, a reciprocatory gate movable on guide-ways 60 on the tilted section of the frame below the driving shaft, and actuating connection between said gate and the driving shaft, a reciprocatory gate mounted on guide-ways on the upper frame above the die bed, rods 65 connecting the lower gate and the upper

gate, said rods being unsupported by the frame, and means securing the rods to the gates.

5. A press comprising a frame, a die bed on the frame, a die mounted on the die bed, 70 a driving shaft supported by the frame below the die bed, a reciprocatory gate movable on guide-ways on the frame below the driving shaft, an actuating connection between said gate and the driving shaft, a reciprocatory gate movable on guide-ways on the frame above the die bed, a punch carried by said upper gate, rods connecting the lower gate and the upper gate, said rods 75 being unsupported by the frame, means securing the rods to the gates, a reciprocatory gate movable on ways on the frame below the first mentioned gate, an actuating connection between the driving shaft and said last mentioned gate, a crosshead above the 80 second mentioned gate, rods connecting the lowest gate with said crosshead, and a punch ram extending from the crosshead through and guided by the upper gate.

6. A press comprising a frame, a die bed 90 on the frame, a die mounted on the die bed, a driving shaft with crank and cams supported by the frame below the die bed, a reciprocatory gate movable on guide-ways on the frame below the driving shaft, an 95 actuating connection between said cams and said gate, a reciprocatory gate movable on the guide-ways on the frame above the die bed, a punch carried by said upper gate, rods connecting the lower gate and the upper gate, said rods being unsupported by the frame, means securing the rods to the gates, a reciprocatory gate movable on guide-ways on the frame below the first mentioned gate, an actuating connection between said 100 crank and the last mentioned gate, a crosshead above the second mentioned gate, rods connecting the lowest gate with said crosshead, and a punch ram extending from the crosshead through and guided by the upper 105 gate.

7. A press comprising a frame and die bed fixed on the frame below the top thereof, a die mounted on the die bed, a reciprocatory gate movable on and guided by the 115 frame below the die bed, a reciprocatory gate movable on and guided by the frame above the die bed, a punch carried by said upper gate, rods connecting the lower gate and the upper gate, said rods passing freely 120 through openings in the frame and in the gates, which openings are considerably larger in diameter than the diameters of the rods, and means for securing the rods to the gates after the gates have been located.

8. A press comprising a frame and die bed fixed on the frame below the top thereof, a die mounted on the die bed, a reciprocatory gate movable on and guided by the 130

frame below the die bed, a reciprocating fixed die bed intermediate the ends of the frame, a gate movable on and guided by the frame above the die bed, a punch carried by said upper gate, rods connecting the lower gate and the upper gate, said rods passing through holes in the gates that are considerably larger in diameter than the diameters of the rods, and means for securing the rods to the gates after the gates have been located.

5

9. A press comprising a frame with a
